US00D816666S

(12) **United States Design Patent** (10) **Patent No.:** **US D816,666 S**
(45) **Date of Patent:** **** May 1, 2018**

(54) **TABLET COMPUTER**

(71) Applicant: **LENOVO (BEIJING) CO., LTD.,**
Beijing (CN)

(72) Inventor: **Hao Jiang**, Beijing (CN)

(73) Assignee: **LENOVO (BEIJING) CO., LTD.,**
Beijing (CN)

(**) Term: **15 Years**

(21) Appl. No.: **35/501,119**

(22) Filed: **Feb. 24, 2016**

(80) **Hague Agreement Data**

Int. Filing Date: **Feb. 24, 2016**

Int. Reg. No.: **DM/090986**

Int. Reg. Date: **Feb. 24, 2016**

Int. Reg. Pub. Date: **Jun. 17, 2016**

(30) **Foreign Application Priority Data**

Oct. 30, 2015 (CN) 2015 3 0427189

(51) **LOC (11) Cl.** **14-02**

(52) **U.S. Cl.**

USPC **D14/341**
